(57) **CLAIM**

I claim the ornamental design for a fish lure silhouette, as shown and described.

DESCRIPTION

FIG. 1 is a top plan view of a fish lure silhouette showing my new design, it being understood the bottom view is a mirror image thereof;

FIG. 2 is a side elevational view thereof, it being understood that the opposite side is a mirror image;

FIG. 3 is a front elevational view thereof;

FIG. 4 is a rear elevational view thereof; and,

FIG. 5 is a top plan view of a second embodiment, the bottom view being a mirror image thereof with a thickness the same as FIG. 2 and end views the same as FIG. 3 and FIG. 4.

A special feature in the design fully shown in the drawings, but not fully appreciated by just the drawings, is the actual thickness of the material which is a relatively thin sheet of material.
